UNITED STATES PATENT OFFICE.

JAMES R. KEARNEY, OF KANSAS CITY, MISSOURI.

GROUND ANCHOR.

Application filed July 5, 1922. Serial No. 572,787.

Figure 1 is a view illustrating the manner of using my improved ground anchor.

Figure 2 is a top plan view of the anchor.

Figure 3 is a side elevational view of said anchor.

Figure 4 is an enlarged inverted plan view of a portion of the anchor.

Figure 5 is a sectional view on line 5—5 of Figure 4.

Figure 6 is a sectional view on line 6—6 of Figure 5.

This invention relates to a new and useful improvement in ground anchors such as are employed in connection with rods to which guy ropes, cables, etc., may be connected.

In using ground anchors of the type herein contemplated, an opening, such as indicated at A in the drawing, is preferably formed in the ground by a posthole digger or other implement and at an angle, as shown. The guy rod B is then driven through the ground so that its inner threaded end projects into the opening A, as shown in Figure 1, after which the ground anchor is engaged with the threaded end of the guy rod and said guy rod turned so as to seat its threaded end into the anchor. The guy rod B may have an eye C formed on its outer end, to which eye is intended to be secured the end of the cable or rope to be anchored.

In the drawings, 1 indicates the body portion of the ground anchor which is preferably formed with an upper convex surface, above which extend ribs 2, the height of said ribs increasing towards the center of the anchor where they are conjoined to the ribs 3 and 4, which, with the web wall 5 forms a boxlike structure.

7 indicates a pivot pin passing through this boxlike structure, on which are pivotally mounted jaws 8, said jaws having flaring walls 9 at their outer ends and registering semicylindrical threaded openings 10 in their adjacent faces.

The construction as above described is disclosed in my companion application filed April 22, 1922, Serial No. 556,276.

My present invention contemplates the use of a separate nut into which the lower end of a guy rod may be turned, instead of securing said threaded end of the guy rod into a threaded opening formed in the body portion of the anchor, as disclosed in my aforesaid application. Guy rods are manu-

factured with threads on their ends produced by different methods. Some guy rods have their threads produced by a roller action, while the threads are cut on other rods. The result is that a nut or threaded opening which is designed with a rod that has a rolled thread is not adapted to receive a rod with a cut thread, and vice versa. I, therefore, propose to provide a pocket or seat on the underside of the body of the anchor, preferably formed by the walls 13 at the junction of the diagonally arranged reinforcing ribs 12, said walls 13 forming a pocket either square or hexagonal depending upon the shape of the nut it receives and each wall 13 being provided with a thin lip 14.

15 indicates a nut designed to be seated in the pocket, said nut being threaded correspondingly to the threads on the anchor rod with which it is to be used, i. e., having rolled or cut threads as the case may be. After the nut is in position, the lips 14 are bent or peened over to hold the nut in place.

I prefer to thread the semicircular openings 10 in the pivotal jaws after the nut 15 is placed in position using the threaded opening in nut 15 as a guide for the tap which forms the threaded openings 10 in the jaws, thus insuring correct registration of the threaded openings 10 and the threaded opening in the nut 15.

One end of the body of the anchor is provided with perforations 16 and a notch 17 for use in connection with a positioning implement 18 which forms no part of my present invention. However, I will state that after the hole A is dug and the guy rod B is arranged in position, as indicated, the anchor is introduced into the opening A by the positioning implement 18 (Figure 1), the operator forcing the anchor upon the end of the rod until the threaded portion of the rod is forced between the spring held jaws and the threads of the rod engage the semicylindrical registering openings in the spring held jaws. When such engagement is effected, the rod 18 is disengaged from the ground anchor. The converging ribs 2 will help guide the end of rod B between the jaws and into the recess formed by the overhanging shelf.

The guy rod having been engaged between the jaws, said rod is rotated so as to turn its threaded end beyond the jaws and

into the threaded opening in the nut, thus fixing the anchor on the end of the rod. When the anchor is so fixed, the earth is replaced in the opening A, and preferably tamped by the widened end 19 of the positioning rod.

If at any time, it is desired to remove the guy rod, it may be unscrewed and withdrawn, and the anchor may be left in the ground, or may be dug up, if desired.

10 The boxlike structure which houses in the movable jaws and their spring, serves to protect these moving parts from the entrance of dirt or other foreign particles which 15 might interfere with their operation at the time that the ground anchor is being introduced into position on the guy rod. After the guy rod is engaged with the movable jaws, then dirt packed behind said jaws and 20 in the space between the jaws and the housing serves to hold said jaws fixed, and, hence, is not objectionable.

When the rod is screwed into the anchor, its threads pass from engagement with the 25 threads of the movable jaws, into engagement with the threads in the opening in the nut, and, hence, the rod has a solid threaded engagement with said nut and said anchor plate. It is obvious that the rod may be 30 unscrewed from the plate at any time even though the anchor plate per se should be abandoned.

What I claim is:—

1. In a ground anchor, a body portion, a 35 nut secured thereto, and flexible means mounted on the body for receiving and hold-

ing a guy rod in a predetermined position to engage said nut.

2. In a ground anchor, a body, a nut secured thereon, and resilient means for 40 guiding a threaded guy rod, moved transversely of the axis of said nut, into proper relation to said nut whereby threaded engagement may be effected.

3. A ground anchor comprising a body 45 portion, a nut secured therein on one side thereof, and guiding means on the opposite side of said anchor for predetermining the position of a guy rod relative to said nut, said guiding means comprising yielding 50 jaws for receiving and guiding said rod.

4. A ground anchor comprising a body portion having a boxlike housing on its upper side, a pair of spring held jaws arranged in said housing for engagement with a guy rod, the contiguous faces of said jaws being provided with registering threaded semicylindrical recesses, and a nut arranged in position on said body portion and provided with a threaded opening for 60 receiving said guy rod.

5. In combination, a ground anchor comprising an anchor plate, a nut having threaded openings and fixedly secured in position on said plate, a guy rod adapted for 65 threaded engagement with and disengagement from said nut, and means for guiding said guy rod into position to engage the threaded opening in said nut.

In testimony whereof I hereunto affix my 70 signature this 28th day of June, 1922.

JAMES R. KEARNEY.
